UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR IN REGULARLY-MOVING TRANSFERRER.

Application filed July 3, 1926. Serial No. 120,490.

This invention relates to improvements in weft detectors for looms and it is the general object of the invention to provide a detector which derives its indicating movement from 5 the inertia of a moving weighted part connected to the detector.

It is a well known property of matter that a weighted mass will resist a change in its rate of movement and if brought to rest 10 suddenly will do work while giving up its motion. While this principle is applicable to a variety of detectors I have chosen to illustrate it in connection with a caliper feeler mounted in a regularly moving trans- 15 ferrer of an automatic weft replenishing loom.

When starting up a loom with a new warp it is frequently desirable to turn the loom over by hand but with the detectors 20 commonly employed this is likely to be accompanied by an indication of the magazine and subsequent replenishment. This action of the magazine is uncalled for and 25 objectionable and it is a further object of my present invention to provide a detector which will depend for its operation upon a certain predetermined rate of running which will normally be in excess of that 30 which can be attained by hand operation.

When a detector of the type set forth in 35 patent to Ryon No. 1,372,316 is employed it is found that the yarn engaging surface rests on the top of the bobbin during the forward and back movement of the lay for a length 40 of time sufficient to cause wearing and it is a further object of my invention to reduce the time of contact between the detector and the yarn by causing the detector to start moving downwardly only after the trans- 45 ferrer has reached its lowest position and then to remove the same from contact with the bobbin by spring action.

With these and other objects in view 50 which will appear as the description proceeds, my invention resides in the combination and arrangement of parts hereinafter described and set forth in the claims.

In the accompanying drawings wherein I 55 have shown a convenient embodiment of my invention.

Fig. 1 is a side elevation of a loom having my invention applied thereto showing certain parts in section,

Fig. 2 is an enlarged front elevation of

the transerrer arm and detector looking 55 in the direction of arrow 2, Fig. 1, with the detector cooperating with a full bobbin,

Fig. 3 is a vertical central section through the transerrer arm in a direction parallel to the axis of the bobbin, showing the detector in indicating position when cooperating 60 with a depleted bobbin,

Fig. 4 is a top plan view in the direction of arrow 4, Fig. 2, and

Fig. 5 is a vertical section on line 5—5 65 of Fig. 3.

Referring to the drawings it will be seen that I have provided a loom frame 10 and a lay 11 which normally moves back and forth toward and from the breast beam 12. 70 The magazine M has a transerrer arm 13 pivoted at 14 and connected to a link 15 the lower end of which is operatively connected to a lever 16 pivoted at 17 to some part of the loom structure. Said lever is provided 75 with a roll 18 received by groove 19 of a cam 20 secured to the bottom shaft 21. The shaft 21 makes a revolution every other pick of the loom and causes a downward movement of transerrer arm 13 when the shuttle 80 S is on the magazine side of the loom. This part of the construction is substantially the same as that set forth in the aforesaid patent to Ryon.

The controlling mechanism for the magazine comprises a plunger 22 slidably mounted in the transerrer arm 13 and having a shoulder 23 which receives the outward thrust of a compression spring 24 the other 85 end of which bears against a clip 25 secured 90 to the transerrer arm by a screw 26. The plunger has a head 27 which engages the clip 25 to limit outward movement of the plunger 22 under action of spring 24 when the head 27 is released.

The plunger is normally held in the retracted position shown in Fig. 2 by the hook 28 of a latch 29 pivoted as at 30 to the transerrer arm. Said latch 29 has a depending tail 31 and contact between the 100 latch 29 and head 27 is insured by a spring 32 held to a part of the transerrer arm by a screw 33. The plunger and latch may be substantially the same as set forth in co- 105 pending application Ser. No. 78,181.

In carrying out my present improvements I provide each side of the slot 40 which extends vertically through the transerrer

arm with a groove 41 and mount for vertical motion in said grooves a detector element 42 the upper end of which is operatively engaged with a spring 43 which may conveniently be secured to the transferrer arm by screw 33. The normal action of the spring 43 is to hold the detector member 42 in the raised position indicated in Fig. 2.

An actuator 44 is pivoted to the detector 10 as at 45 and has an upstanding finger 46 positioned for operative engagement with the tail 31. The lower end of the actuator is offset and notched as at 47 and extends between the opposite prongs 48 extending 15 downwardly from the bottom of the detector member 42. Said prongs have broadened pads 49 which present a relatively large yarn engaging surface which will not fray or abrade the yarn.

20 As the transferrer arm descends the sliding detector 42 will be in raised position, being held so by spring 43. When the transferrer reaches the bottom of its stroke the detector, due to its weight and inertia, 25 will tend to continue to move down against the action of spring 43 to present the pads 49 to the yarn.

Under normal conditions when a sufficient supply of weft for continued weaving is 30 present the transferrer arm 13 will be brought down to the position indicated in Fig. 2, the diameter of the weft W on the bottom B being such as to prevent downward motion of the pads 39 sufficient to permit finger 46 to engage tail 31. When the yarn is substantially depleted, however, and the transferrer moves to its lowest position the detector member 42 will continue its downward movement due to the inertia 40 thereof and the pads 49 will pass down on the opposite sides of the bobbin as indicated in Fig. 5. This downward movement causes engagement between the offset end 47 of the controller 44 and the bobbin and 45 results in an angular movement of the controller relatively to the detector. When in the position indicated in Figs. 3 and 5 the finger 46 is sufficiently below the pivot 30 of the latch to move the latter angularly in 50 a left hand direction so as to move lever 28 out of contact with the head 27, after which the plunger 22 will move to the right under the action of spring 24. At all other times the finger 46 will strike the tail 31 at a 55 point sufficiently close to the pivot of the latch to prevent movement of the latter should the controller 44 move accidentally on its pivot. Movement of the plunger 22 to the right as shown in Fig. 3 results in 60 indication of weft change as set forth in the aforesaid patent to Ryon.

Immediately after the detector 42 has moved to the low position indicated in Fig. 5 and has spent its inertia the spring 43 acting independently of the upward move-

ment of the transferrer arm will raise the detector 42.

From the foregoing it will be seen that I have provided a detector which depends for its operation upon the inertia of a moving part and it is to be understood that the principle set forth herein is not limited to the form of detector shown, the detector in the transferrer being set forth merely to illustrate one embodiment of the invention. 70 It will also be seen that the detector will start back to normal position under action of the spring 43 independently of the particular position of the transferrer arm. Furthermore, a slow turning over of the 75 loom such as results from hand operation will not give the detector 42 a downward motion of sufficient rapidity to cause an indication and it is therefore unnecessary to provide an auxiliary device to prevent indication of weft exhaustion as is the case with the usual form of detector. Again, it will be seen that the detector does not start toward operative engaging position until the transferrer has actually come to rest at 80 the lower limit of its motion and the result of this is that the detector is in contact with the yarn a very short time.

Having thus described my invention, it will be apparent that changes and modifications may be made therein by those skilled in the art without departing from the spirit and scope of the invention, and I do not wish to be limited to the details herein disclosed but what I claim is:

1. In a weft detector for a loom having a surface to be detected, a detector to cooperate with the surface, means to cause relative motion between the detector and the surface to lessen the distance between said detector and surface, a support for the detector, means exerting a force on the detector to cause the latter to maintain the same relative position with respect to the support during the time that the distance between the surface and detector is being reduced, means to cause an abrupt change in the force acting on the detector as the distance between the detector and surface is reduced, a weighted mass operatively connected to the detector and tending to act by the inertia thereof at the time of said abrupt change to cause a relative change in the relation of the detector and support therefor and tending to give the detector an 105 indicating movement while in contact with the surface.

2. In a weft detector for a loom having a surface to be detected, a weighted detector to cooperate with the surface, means to exert a force on the detector tending to move the same toward the surface to be detected, and means to cause an abrupt change in the application of the force to the detector, the energy stored in the weighted detector act- 110 120 125 130

ing to move the same into contact with the surface to be detected after the abrupt change in the application of the force and tending to move the detector to indicating position.

5 3. In a weft detector for looms having a surface to be detected, a weft detector to cooperate with the surface, a support for the detector, means to cause and arrest relative movement between the support and the surface, and weighted means operatively connected to the detector and acting by reason of the inertia thereof to tend to give the detector an operative movement when the said relative movement of the support is arrested.

4. In a weft detector for looms having a surface to be detected, a detector to cooperate with the surface, a support for the detector with respect to which the detector is movable, weighted means operatively connected to the detector and mounted for movement relatively to the support, and means to cause and arrest movement of the support toward the surface, the inertia of the weighted means exerting a force on the detector tending to give the same an indicating movement when the movement of the support is arrested.

30 5. In a weft detector for looms having a surface to be detected, a detector to cooperate with the surface, a movable support for the detector movable to cause relative movement of the detector and surface, means to arrest the movement of the support, and a weighted member effective by the inertia thereof after the movement of the support has ceased to move the detector toward the surface and tending to give the same an indicating movement.

40 6. In a weft detector for looms having a surface to be detected, a detector to cooperate with the surface, a weighted member operatively connected to the detector and freely movable, means to move the detector and the weighted member toward the surface, and means to arrest such motion, the detector being acted upon by the weighted member when the motion is arrested to tend to give the detector an indicating movement.

50 7. In a weft detector for looms having a surface to be detected, a weft detector to cooperate with the surface, a support for the detector, means to cause and arrest relative movement between the support and the surface, weighted means operatively connected to the detector and acting by reason of the inertia thereof to tend to give the detector an operative movement when the said relative movement of the support is arrested, and resilient means to restore the detector and weighted means to normal position.

60 8. In a weft detector for looms having a surface to be detected, a detector to cooperate with the surface, a movable support

for the detector movable to cause relative movement of the detector and surface, means to arrest the movement of the support, a weighted member effective by the inertia thereof after the movement of the support has ceased to move the detector toward the surface and tending to give the same an indicating movement, and resilient means to restore the detector and weighted member to normal position.

70 9. In a weft detector for looms having a surface to be detected, a weighted detector to cooperate with the surface, a support for the detector with respect to which the detector is movable, yielding means to hold the detector away from the surface, the inertia of the weighted detector being operative when the relative motion is arrested to overcome the yielding means and move the detector toward the surface and tend to give the same an indicating movement.

75 10. In a weft detector for looms having a surface to be detected, a weighted detector to cooperate with the surface, a support on which the detector is freely movable, means to move the support toward the surface to be detected, and means to arrest movement of the support toward the surface, the arresting of the movement tending to cause the weighted detector because of the inertia thereof to continue to move toward the surface and to tend to give the detector an indicating movement.

80 11. In a weft detector for looms having a surface to be detected, a weighted detector to cooperate with the surface, a support on which the detector is freely movable, resilient means interposed between the support and the detector to hold the latter away from the surface, means to move the support and detector toward the surface, and means to arrest such motion, the arresting of the movement of the support toward the surface causing the weighted detector because of the inertia thereof to overcome the resilient means and move toward the surface and tend to have an indicating movement.

85 12. In a weft detector for looms having a surface to be detected, a transerrer arm, means to cause and arrest movement of the transerrer arm toward the surface to be detected, and a weighted detector supported by but freely movable with respect to the transerrer arm and normally held away from the surface, said weighted detector because of the inertia thereof moving toward the surface as the transerrer arm is arrested in its movement toward the surface.

90 13. In a weft detector for looms having a surface to be detected, a transerrer arm movable toward and from the surface to be detected, a weighted weft detector freely movable on the transerrer arm toward and from the surface to be detected, and resilient means acting normally to hold the detector

away from the surface, the detector because of its inertia tending to continue its motion toward the surface against the action of the resilient means when the transerrer arm 5 stops moving toward and starts to move from the surface to be detected.

14. In a weft detector for looms having a surface to be detected, a transerrer arm, means to cause and arrest movement of the same toward the surface to be detected, a spring pressed plunger on the arm, a latch normally holding the plunger in inoperative position, a weighted detector supported by and freely movable with respect to the transerrer arm, the detector because of the inertia thereof being moved toward the surface as the transerrer arm is arrested in its motion, and means actuated by the detector to release the latch and plunger when the 20 detector moves toward a surface having an insufficient supply of weft.

15. In a weft detector for looms having a

surface to be detected, a transerrer arm, means to cause and arrest movement of the same toward the surface to be detected, a 25 spring pressed plunger on the arm, a latch normally holding the plunger in inoperative position, a weighted detector supported by and freely movable with respect to the transerrer arm, the detector because of the inertia thereof being moved toward the surface as the transerrer arm is arrested in its motion, means actuated by the detector to release the latch and plunger when the detector moves toward a surface having an insufficient supply of weft, and resilient means connected to the arm and detector to hold the latter normally away from the surface, the inertia of the detector overcoming 30 said means when the transerrer arm is arrested.

35 In testimony whereof I have hereunto affixed my signature.

RICHARD G. TURNER.
